CURTAIN STRETCHER

Albert H. Moore, Alliance, Ohio

Application June 18, 1934, Serial No. 731,041

16 Claims. (Cl. 45—24)

This invention relates to curtain stretchers such as are used for drying curtains, draperies or the like after being washed, and more especially it relates to improved curtain stretchers of the type 5 wherein the curtain or drape mounted thereon is folded at its middle and its respective end portions disposed in parallel relation to each other.

The chief objects of the invention are to conserve space both in the operative condition of the 10 device and when disassembled for storage; to provide improved means for holding the structure in assembled condition, which means permits of ready adjustability of the device for curtains of different widths; to provide novel and 15 improved means for adjusting the structure to receive curtains of different lengths; to provide improved pins or hooks for engagement with the lateral marginal portions of a curtain; and to provide readily for the removal of said pins or 20 hooks to facilitate disassembly of the stretcher for storage. Other objects will be manifest as the specification proceeds.

Of the accompanying drawings,

Figure 1 is a front elevation of curtain stretcher embodying the invention, in its preferred form;

Figure 2 is an end elevation thereof;

Figure 3 is a section, on a larger scale, on the line 3—3 of Figure 1, and a curtain in place thereon;

Figure 4 is a fragmentary detail end elevation, on a larger scale, showing the means for engaging the respective end portions of a curtain;

Figure 5 is a section on the line 5—5 of Figure 4; and

Figure 6 is a view similar to Figure 4 showing modified means for engaging the end portions of a curtain.

Referring to the drawings, 10, 10 are parallel, spaced standards that are supported in vertical position by respective feet or sills 11, 11, the latter being transversely slotted to receive the standards. The sills and standards are secured together by respective bolts 12, 12 that are provided with wing nuts to permit rapid assembly 40 and disassembly. A bottom rail 13, which may be calibrated as shown, extends from one foot 11 to the other, and is removably clamped to the respective standards 10 by bolts 14. Rail 13 assists in imparting rigidity to the structure.

Mounted upon the top of standards 10 is a top rail 16 that has its upper face rounded as shown so that said rail is substantially semi-cylindrical in form. Secured to the under side of top rail 16 and extending longitudinally thereof is a 55 tongue 17, said tongue being considerably nar-

rower than the rail 16 and being centrally disposed with relation to the lateral margins thereof. The tongue 17 is received in complementally shaped slots 18 formed in the tops of standards 10, and the lateral faces of the tongue are formed with respective longitudinally extending rabbets or slots 19, 19. The standards, sills and rails previously described preferably are made of wood.

Secured to the adjacent faces of standards 10 near the top thereof are respective sheet metal brackets 21. Each bracket 21 is angular in shape, and has a portion 21^a thereof that projects laterally from the standard, parallel to tongue 17, and has its upper marginal portion bent at right angles to form a flange 21^b, Figure 3, that engages in one of the rabbets 19 of said tongue. The brackets 21 are identical in structure and are so mounted that the flange 21^b of one engages one rabbet 19 whereas the flange 21^b of the other bracket engages in the rabbet on the opposite side of the tongue. Associated with each bracket 21 is an L-shaped metal clamp 22 that is secured thereto by a bolt 23 provided with wing nut 24. The clamp 22 is so positioned that one of its margins bears against bracket portion 21^a and an opposite side bears against a side of tongue 17, the arrangement being such that tightening of bolt 23 clamps tongue 17 between clamp 22 and bracket portion 21^a. The construction makes for easy adjustability of the standards 10 relatively of the top rail 16, yet provides for ample rigidity of the assembled structure. As is most clearly shown in Figure 3, a curtain designated 25, when mounted on the stretcher extends over the rounded top of top rail 16 and downwardly each side thereof, the bolts 23 and wing nuts 24 being so positioned inwardly of the lateral margins of the top rail as not to be in contact with the curtain.

For engaging the respective end portions of the curtain 25, flat metal stretcher bars 27, 27 are provided, which bars are insertable through the hem at the respective ends of the curtain, as is most clearly shown in Figure 4. This figure shows an extra pair of bars 27 which may be used when it is desired to dry and stretch two curtains of the same size at one time. The bars 27 of each pair of bars are disposed on opposite sides of standards 10; and their respective end portions are engaged in vertically adjustable fixtures whereby the stretcher is adaptable for curtains of any length. Said fixtures are mounted on the outer faces of standards 10 and are identical in structure so that a description of one will suffice for both, attention being especially directed to Figures 4 and 5.

Each of said fixtures comprises a metal plate 29 that has each of its lateral margins formed with an integral arm or extension 30 that is disposed at right angles to plate 29, said arms 30 being parallel to each other and adapted to embrace the standard 10 on which the fixture is mounted. The free ends of arms 30 are connected by a bolt 31 that is provided with a wing nut 32, the arrangement being such that tightening of 10 said wing nut causes the fixture to be tightly clamped in fixed position on the standard, yet being adapted for vertical adjustment thereon upon loosening of said wing nut.

The upper part of plate 29 is bent outwardly at 15 right angles to provide a projecting shelf 34 upon which rests a pair of heavy wire clips 35, 35. The clips 35 are adjustably secured in position on shelf 34 by a metal cleat 36 that carries a bolt 37, the latter extending between clips 35 and through a 20 suitable aperture in shelf 34, there being a wing nut 38 threaded onto said bolt below said shelf. The clips 35 have limited longitudinal movement relatively of cleat 36 when the wing nut 38 is loosened. Said clips extend from each side of 25 standard 10, and each has one end formed with a downwardly extending hook portion 35a adapted to embrace one or more bars 27, the latter being disposed below the clips. The other end of each clip is angularly bent as shown to prevent the 30 clip from being removed from beneath cleat 36 when the latter is loosened.

In order to prevent the lateral margins of the curtain 25 from pulling toward each other as the curtain is stretched longitudinally, means is provided for securely anchoring said marginal portions to the stretcher structure, and to this end each standard 10 is formed with a longitudinal series of transverse apertures or sockets 40, 40 that extend from the inner face to the outer 40 face of the standard and selectively receive respective pins 41. Each pin 41 consists of a single length of wire that is sharpened at both ends, and has its medial portion so bent as to provide a transversely disposed portion 41a of double 45 thickness. The portion 41a of each pin is received in a socket 40, the pointed ends of the pin projecting beyond the front and rear faces of the standard 10, as shown in Figures 2 and 5, so that the marginal portions of the curtain 25, 50 on opposite sides of the standards, may be attached to said pins. The springiness of the wire of pins 41 holds them securely in their sockets, yet they are easily removed therefrom before the stretcher is disassembled so that there is little 55 danger of lacerating the hands. The pins 41 are mounted in place after the stretcher is assembled for use, and if the stretcher is not used to its fullest capacity, all of the pins will not require to be mounted.

60 It will be seen that the standards 10 may be adjusted relatively of each other to accommodate curtains of different widths, and that by raising or lowering the fixtures that engage stretcher bars 27 the device can be made to accommodate 65 curtains of different lengths. The stretcher is of relatively small area when assembled and may be disassembled and packed within small compass.

The modified embodiment shown in Figure 6 is 70 identical in all respects with the preferred embodiment of the invention except that stretcher bars 27 are dispensed with and in their place is provided wooden rails 43, 43, which rails are provided with respective series of outwardly projecting pins 44 upon which the respective end 75 portions of a curtain may be impaled. The rails

43 are of irregular transverse shape as shown to provide a ledge 43a, and in use the clips 35 are turned so that their hook-shape end portions 35a extend upwardly so as to engage said ledge, whereby the said rails are securely held in proper position. The provision of the rails 43 makes the device available for stretching curtains not provided with hems at their ends. 5

Other modifications may be resorted to without departing from the spirit of the invention or the 10 scope of the appended claims.

What is claimed is:

1. In a curtain stretcher, the combination of a pair of vertical standards, a semicylindrical top rail mounted upon the tops of said standards, 15 said top rail being provided with a relatively narrow longitudinal tongue on its bottom face seating in respective grooves in the top of the respective standards, means mounted upon said standards and engaging said tongue for adjustably securing the top rail to the standards, said means being disposed between the lateral margins of the top rail, vertically adjustable means for engaging both ends of a curtain that extends over said top rail, and respective series of pins 20 removably mounted on the outer face of each standard for impaling the lateral margins of said curtain, each of said pins being double pointed so as to engage the curtain on opposite sides of the standard. 30

2. In a curtain stretcher, the combination of a pair of vertical standards, a semicylindrical top rail mounted upon the tops of said standards, the lateral margins of said top rail being flush with the front and rear faces of the standards, means 35 disposed between the standards for adjustably securing the top rail to the standards, vertically adjustable means attached to the standards for engaging both ends of a curtain that extends over said top rail, and respective series of pins 40 removably mounted on the outer side of each standard for impaling the lateral margins of the said curtain.

3. A curtain stretcher comprising a pair of vertical standards, a semicylindrical top rail of the 45 same width as the standards supported upon the tops thereof, and means disposed between the standards and below the top rail for adjustably securing the top rail to the standards in a manner that permits adjustment of the standards 50 longitudinally of the top rail.

4. A curtain stretcher comprising a pair of vertical standards, a transversely rounded top rail supported upon the tops thereof, and means 55 permanently secured to the respective standards and releasably engaging the under side of the top rail for adjustably holding them together, said securing means being disposed entirely between the lateral margins of the top rail.

5. A curtain stretcher comprising a pair of vertical standards, a half-round top rail across the upper ends thereof, a tongue on the under side of the top rail seating in complementary slots formed in the ends of the standards, and means 60 permanently secured to the standards and releasably engaging said tongue for holding the structure adjustably in assembled condition. 65

6. A curtain stretcher comprising a pair of vertical standards, a rounded top rail across the upper ends thereof, a tongue on the under side 70 of the top rail seated in complementary grooves formed in the ends of the respective standards, said tongue being formed with longitudinally extending rabbets, and means secured to the standards and releasably engaging in the rabbets 75.

of said tongue for holding the structure adjustably in assembled condition.

7. A curtain stretcher comprising a pair of vertical standards, a rounded top rail across the upper ends thereof, a tongue on the under side of the top rail seated in complementary grooves formed in the ends of the respective standards, said tongue being formed in its respective lateral faces with longitudinally extending rabbets, 10 brackets secured to each standard and formed with a flange engaging in a rabbet in said tongue, and a releasable clamp on each bracket engaging said tongue for holding the structure adjustably in assembled condition.

15 8. A curtain stretcher comprising a pair of parallel side members, an end rail across the ends thereof, a tongue on said end rail seated in complementary grooves in the ends of the respective side members, said tongue being formed 20 with longitudinally extending rabbets, and means secured to the adjacent faces of the side members and releasably engaging in the rabbets of said tongue for holding the structure adjustably in assembled relation, said means being disposed entirely between the lateral margins of 25 the end rail.

9. A curtain stretcher comprising a pair of vertical standards, a rounded top rail supported on the tops thereof and adapted to receive the medial portion of a curtain thereover, a pair of flat stretcher bars adapted to be inserted in hems at the respective ends of a curtain, and a single fixture on each standard for securing both bars to the respective standards on opposite sides 35 thereof.

10. A curtain stretcher comprising a pair of vertical standards, a rounded top rail supported on the tops thereof and adapted to support the medial portion of one or more curtains thereon, 40 stretcher bars for insertion in the hems at the respective ends of said curtains, fixtures on the respective standards adjustable longitudinally thereof, and a pair of oppositely extending, laterally adjustable clips on each fixture for engaging 45 one or more stretcher bars at opposite ends of the curtains and on opposite sides of the standards.

11. A curtain stretcher comprising a pair of vertical standards, a rounded top rail supported 50 on the tops thereof and adapted to support the medial portion of one or more curtains draped thereover, stretcher bars for insertion in the hems at the respective ends of the curtains, said bars being disposed on opposite sides of the standards, fixtures on the respective standards adjustable longitudinally thereof, pairs of reversely disposed clips for engaging the stretcher bars at 55 opposite ends of the curtains, and removable

cleats for adjustably securing respective pairs of clips to respective fixtures.

12. A curtain stretcher comprising a pair of parallel side members, an end rail across the ends thereof adapted to engage the medial portion of a curtain mounted upon the stretcher, a pair of stretcher rails extending transversely of the side members, at opposite sides thereof, said stretcher rails being provided with pins for impaling the respective end portions of a curtain, 10 and means positioned on the outer face of each side member and adjustable longitudinally thereof for engaging and supporting both stretcher rails.

15 13. A curtain stretcher comprising a pair of parallel side members each having its outer face formed with a longitudinal series of sockets, an end rail across the ends of said members adapted 20 to engage the medial portion of a curtain mounted upon the stretcher, means extending transversely of said side members and secured thereto for engaging the respective end portions of the curtain, and respective pins mounted in the aforesaid sockets in the outer face of each side member, each of said pins having two points which 25 project beyond opposite margins of said side member for engagement with lateral margins of the curtain on opposite sides of the stretcher, and each pin having an offset portion receivable in 30 a socket.

14. The combination of a curtain stretcher having lateral frame elements formed with apertures, and a double pointed pin having a central offset portion receivable in one of said apertures, the pin being of such length that its pointed 35 ends project beyond opposite margins of said frame element, the apertures and the offset portion of the pins being of such relative size as to effect frictional engagement therebetween.

15. The combination of a curtain stretcher having lateral frame elements formed with apertures, and a pin sharpened at both ends and having a portion of double thickness extending at right angles from its middle, said double thickness portion being receivable in one of said apertures 45 in the frame element, and having sufficient springiness to frictionally engage the opposite sides of the aperture.

16. The combination with a curtain stretcher having frame elements formed with longitudinal 50 series of sockets therein, of respective pins removably mountable in said sockets, each pin consisting of a single length of wire pointed at both ends and having its central portion bent double to provide an integral, laterally extending portion of such size as to seat within one of said sockets in yielding engagement with the wall of 55 said socket.

ALBERT H. MOORE.
